UNITED STATES PATENT OFFICE.

CHARLES F. EDGARTON, OF SHIRLEY, MASSACHUSETTS, ASSIGNOR TO THE
C. A. EDGARTON MANUFACTURING COMPANY, OF SAME PLACE.

DESIGN FOR A SUSPENDER-END.

SPECIFICATION forming part of Design No. 28,792, dated June 7, 1898.

Application filed March 14, 1898. Serial No. 673,870. Term of patent 14 years.

To all whom it may concern:

Be it known that I, CHARLES F. EDGARTON, of Shirley, in the county of Middlesex and State of Massachusetts, have invented and produced a certain new and original Design for Suspender-Ends, of which the following is a specification, reference being had to the accompanying drawing, forming a part thereof.

The drawing represents a front elevation of a suspender-end embodying my design.

The leading feature of my design consists in the form given to the clasp which supports the button-strap and the central depending supporter, said clasp having a front flap, the lower edge of which has an undulating form, the said clasp having a straight lower edge, and the central depending supporter having vertical parallel edges below the clasp.

a is the clasp. *b* is a link for connecting said clasp to the end of the shoulder-strap.

c is the equalizing button-strap, passing through the clasp *a*, and *d* is the central depending supporter or strap, attached to the clasp *a*.

The front portion of the clasp *a* is formed by a flap *a'*, the lower edge of which has an undulating form, as shown, this being a feature of my design. The said edge forms two outwardly and downwardly convex portions 2 2 where it breaks from the vertical side edges of the flap and a downwardly-convex portion 3, constituting an apex for the lower edge of the flap. The convex portions 2 and 3 of this edge are connected by two upwardly and inwardly concave portions 4 4. The other distinguishing feature of my design is the straight lower edge 5 of the clasp *a* and the straight vertical edges 6 6 of the central supporting-strap *d*, which edges form right angles with the edge 5.

I claim—

The design for a suspender-end, substantially as herein shown and described.

CHARLES F. EDGARTON.
